Patented Jan. 29, 1918.

UNITED STATES PATENT OFFICE.

WILLOUGHBY MOULTON AVEBY AND JOHN BINGHAM BOOTH, OF GREENSBORO, NORTH CAROLINA, ASSIGNEES OF TWO-THIRDS TO SAID AVEBY AND ONE-THIRD TO SAID BOOTH.

TRAIN-STOP.

1,254,645.

Specification of Letters Patent. Patented Jan. 29, 1918.

Application filed July 13, 1916. Serial No. 109,101.

To all whom it may concern:

Be it known that we, WILLOUGHBY M. AVEBY and JOHN B. BOOTH, citizens of the United States, and residents of Greensboro, in the county of Guilford and State of North Carolina, have invented an Improvement in Train-Stops, of which the following is a specification.

This invention is an improvement in rail-road appliances and has particular reference to an automatic train stop.

An object of the invention is to provide a novel mechanism for automatically stopping a train should the same, through inadvertence or otherwise, pass a danger signal, and to this end a valve mechanism is operated, by an automatically controlled electric circuit, for establishing communication between the main reservoir of the air brake system and another valve mechanism actuated by air pressure, when said circuit is closed, to shut off the connection between said main reservoir and the train pipe, and, at the same time, permit the escape of air from the latter whereby an application of the brakes is accomplished.

Another object is the provision of suitable means for preventing the release of the brakes after an application thereof until the train is brought to a complete stop, and for this purpose a lock circuit is used in conjunction with a main circuit and automatically closed by the closing of said main circuit to prevent a return of the valve mechanisms to their normal positions.

The inventive idea involved is capable of receiving a variety of mechanical expressions, one of which, is shown in the accompanying drawings, but it is to be expressly understood that said drawing is used merely for the purpose of facilitating the description of the invention as a whole and not to define the limits thereof, reference being had to the appended claims for this purpose.

In the drawings:

Figure 1 is a diagrammatic view of the electric circuits and a sectional view of the valve mechanisms employed in connection with the invention.

Fig. 2 is a transverse section on the line 2-2 of Fig. 1.

Fig. 3 is a similar section on the line 3-3 of Fig. 1.

55 There is illustrated in the accompanying

drawing what is now believed to be a preferred form of the invention, in which there is employed a main circuit consisting of a wire 5 connected at one end to a third rail 6, and at its other end to a suitable terminal on a semaphore device 7 of any ordinary construction. Another wire 8 is also associated with the semaphore 7 and the circuit is closed through said wires, at this point, when the semaphore is in a danger or full line position shown in the figure, the other extremity of the wire 8 is connected to one of the rails 9 upon which the train runs. Electricity is applied to the circuit by means of a car operated low pressure generator 10 having a wire 11 leading therefrom to a magnet 12 with which is associated an armature 13. This armature is normally in connection with one terminal of a wire 14, the other end of which is secured to a suitable contact shoe 15 carried by the train and adapted to engage the third rail 6, which engagement completes the circuit, the same being grounded through the wire 16, solenoid 17 and wire 18. Upon the completion of the circuit the magnet 12 is energized and attracts the armature 13 whereby the same is caused to contact one terminal of wire 19, the other terminal of which is grounded to provide a lock circuit for continuously maintaining a closed circuit until the generator 10 ceases to operate owing to the stoppage of the train.

The valve mechanisms which comprise the essential features of the invention are preferably employed in connection with the air brake system of the train including the supply pipe 20 leading from the main reservoir (not shown) to the usual engineer's valve 21, which controls the air pressure in the train pipe 22. A controlling mechanism is interposed between the engineer's valve and train pipe and preferably comprises a casing 23 having detachable end plates 24 and 25, said casing being connected to the engineer's valve by means of a pipe 26 and to the train pipe, the train pipe 22 communicating with the interior of said casing through a port 27. The casing 23 is provided interiorly with a large piston chamber 28 at one end and a small piston chamber 29 at the opposite end in which chambers are mounted the large and small pistons 30 and 31, respectively. These pistons are preferably carried at each end of

a valve member 32 provided with an opening 33 adapted to normally register with the port 27 whereby communication is established between the engineer's valve and the train pipe and air pressure maintained in the latter. When the valve 32 is operated, in a manner to presently appear, and shifted to the full line position shown in Fig. 1, a longitudinal groove 34 formed in the bottom of said valve member will connect the port 27 with a small bleed port 35 in which position communication between the engineer's valve and the train pipe is shut off and the air pressure from the latter permitted to escape to the atmosphere whereupon an application of the service air brakes will result. The valve 32 is maintained in its normal dotted line position by reason of the fact that the pistons 30 and 31 are of unequal areas and since the pressure of the air entering the casing through the pipe 26 is equal in all directions, the larger piston 30 will be forced to its end 24 of the casing. An escape port 36 is provided in the end 25 of the casing to prevent any accumulation of air pressure, owing to leakage, between the small piston 31 and said end of the casing.

Means are provided for producing an inequality of air pressure in the casing 23 whereby to operate the valve 32 and preferably comprise a branch pipe 37 having one end connected to the end 24 of said casing while the other end is coupled to the main supply pipe 20. Mounted between the ends of the branch pipe 37 there is a valve casing 38 in which is mounted for vertical movement, an electrically controlled valve 39 having a transverse passage 40 therethrough for establishing communication between the supply pipe 20 and the casing 23 when the main or lock circuits previously described are closed. The closing of either of these circuits operates the solenoid 17 which is connected to the valve 39 to lift the same to the full line position shown in the drawing. Admission of air pressure through the pipe 37 into the adjacent end of the casing 23 will produce an inequality of air pressure in said casing which will cause the valve 32, and pistons 30 and 31 to move to the full line position.

When the circuit is broken, by reason of the train coming to a stop and consequent cessation of operation of the generator 10, the valve 39 will drop to its normal position and, through the medium of a longitudinal duct or passage 41 therein, permit the air pressure between the piston 30 and the end 24 of the casing to escape through the branch pipe 37 duct 41 and bleed port 42, in the casing 38, to the atmosphere. It will thus be seen that the invention provides a simple, positive and efficient means for automatically making an application of the air brakes

of the train and preventing the release of said brakes before the train comes to a complete stop.

What is claimed is:

1. In an automatic train stop embodying an air brake system, a valve mechanism disposed between the supply pipe from the main reservoir of the system and the train pipe, and normally held open by the air pressure from the supply pipe, an auxiliary valved connection between the said supply pipe and the valve mechanism for admitting air from the supply pipe to the valve mechanism to operate the latter against the pressure of the air normally acting thereon, and controlling means for the auxiliary valved connection actuated by the motion of the train. 70 75 80

2. In an automatic train stop embodying an air brake system, a valve mechanism disposed between the supply pipe from the main reservoir of the system and the train pipe, and normally held open by the air pressure from the supply pipe, a branch pipe connecting the said supply pipe with the valve mechanism, a controlling valve in the branch pipe normally closing the same, and actuating means for the controlling valve operated by the motion of the train. 85 90 95

3. In an automatic train stop embodying an air brake system, a valve mechanism disposed between the supply pipe from the main reservoir of the system and the train pipe and normally held open by the air pressure from the supply pipe, an auxiliary valved connection between the said supply pipe and the valve mechanism for admitting air from the supply pipe to the valve mechanism to operate the latter against the pressure of the air normally acting thereon, and electrically operated means for actuating the auxiliary valved connection operated by the motion of the train. 100 105 110

4. In an automatic train stop embodying an air brake system, a valve mechanism disposed between the supply pipe from the main reservoir of the system and the train pipe and normally held open by the air pressure from the supply pipe, an auxiliary valved connection between the said supply pipe and the valve mechanism for admitting air from the supply pipe to the valve mechanism to operate the latter against the pressure of the air normally acting thereon, and electrically operated means for actuating the auxiliary valved connection including a current generator operated by the motion of the train. 115 120 125

5. In an automatic train stop embodying an air brake system, a valve mechanism disposed between the supply pipe from the main reservoir of the system and the train pipe including a piston having one face acted upon by the air pressure from the supply pipe, an auxiliary valved connection 130

between the said supply pipe and the valved mechanism for admitting air from the supply pipe to the opposite face of the piston to move the valve mechanism against the pressure of air normally acting thereon, and controlling means for the auxiliary valved connection actuated by the motion of the train.

6. In an automatic train stop, the combination of an electric circuit, an air brake system, means for controlling the passage of air between the supply pipe from the main reservoir of said system and the train pipe and including a casing having piston chambers therein of different areas, pistons mounted in said chambers, a valve connecting said pistons and normally in position to permit passage of air from said supply pipe and said train pipe, means connecting said supply pipe with said casing for producing an inequality of air pressure in the latter whereby said valve and pistons are actuated to produce an application of the brakes, and means operated by said electric circuit for controlling the passage of air through the last-named means.

7. In an automatic train stop, the combination of an electric circuit, an air brake system, means for controlling the passage of air between the supply pipe from the main reservoir of said system and the train pipe and including a casing having piston chambers therein of different areas, pistons mounted in said chambers, a valve connecting said pistons and normally in position to permit passage of air from said supply pipe and said train pipe, means connecting said supply pipe with said casing for producing an inequality of air pressure in the latter whereby said valve and pistons are actuated to produce an application of the brakes, and a valve for controlling the passage of air through the last-named means and normally in a position, when said electric circuit is opened, to permit of the escape of air from said casing whereby an equality of pressure therein is maintained, said last-named valve being operated by the closing of said electric circuit to establish communication between said supply pipe and said casing to cause an inequality of air pressure in the latter.

8. In an automatic train stop, the combination of an automatically controlled electric circuit, an air brake system, means for controlling the passage of air between the supply pipe from the main reservoir of said system and the train pipe and including a casing having piston chambers therein of

different areas, pistons mounted in said chambers, a valve connecting said pistons and normally in position to permit passage of air from said supply pipe and said train pipe, means connecting said supply pipe with said casing for producing an inequality of air pressure in the latter whereby said valve and pistons are actuated to produce an application of the brakes, and means operated by said electric circuit for controlling the passage of air through the last-named means.

9. In an automatic train stop, the combination of an automatically controlled electric circuit, an air brake system, means for controlling the passage of air between the supply pipe from the main reservoir of said system and the train pipe and including a casing having piston chambers therein of different areas, pistons mounted in said chambers, a valve connecting said pistons and normally in position to permit passage of air from said supply pipe and said train pipe, means connecting said supply pipe with said casing for producing an inequality of air pressure in the latter whereby said valve and pistons are actuated to produce an application of the brakes, means operated by said electric circuit for controlling the passage of air through the last-named means, and a second circuit for maintaining the means controlled by first said electric circuit in position to permit of said passage of air during the progress of the train.

10. In an automatic train stop, the combination of an automatic controlled electric circuit, an air brake system, means for controlling the passage of air between the supply pipe from the main reservoir of said system and the train pipe, and including a casing having piston chambers therein of different areas, pistons in said chambers, a valve connecting the pistons and normally in position to permit passage of air from said supply pipe and train pipe, said valve when moved into abnormal position operating to close communication between the said pipes and establish communication between the train pipe and the atmosphere, means connecting the supply pipe with the casing for producing an inequality of air pressure in the latter whereby said valve and pistons are actuated to produce an application of the brakes, and means operated by the electric circuit for controlling the passage of air to the last named means.
